(57) **CLAIM**

The ornamental design for a wall shelf, as shown and described.

DESCRIPTION

FIG. 1 is a front, left and bottom perspective view of a first embodiment of a wall shelf, showing my new design;
FIG. 2 is a rear, right and top perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a front, left and bottom perspective view of a second embodiment of the wall shelf, showing my new design;
FIG. 10 is a rear, right and top perspective view thereof;
FIG. 11 is a front elevation view thereof;
FIG. 12 is a rear elevation view thereof;
FIG. 13 is a left side elevation view thereof;
FIG. 14 is a right side elevation view thereof;
FIG. 15 is a top plan view thereof; and,
FIG. 16 is a bottom plan view thereof.

The broken lines in the figures depict portions of the wall shelf that form no part of the claimed design.
